UNITED STATES PATENT OFFICE.

CASSIUS H. HALSTEAD, OF CHICAGO, ILLINOIS, ASSIGNOR TO CENTRAL BEDDING COMPANY OF ILLINOIS, OF CHICAGO, ILLINOIS, A CORPORATION OF ILLINOIS.

WIRE BED-BOTTOM FABRIC.

No. 904,812.

Specification of Letters Patent. Patented Nov. 24, 1908.

Application filed October 12, 1907. Serial No. 397,166.

To all whom it may concern:

Be it known that I, CASSIUS H. HALSTEAD, a citizen of the United States, residing at Chicago, in the county of Cook and State of Illinois, have invented certain new and useful Improvements in Wire Bed-Bottom Fabrics, of which the following is a specification.

This invention relates to wire fabrics and 10 more particularly to that class of fabrics employed for the bottoms of beds, couches and the like.

More specifically, the invention belongs to 15 that class of wire fabrics wherein are employed a plurality of bent wire units of duplicate form and structure throughout and arranged in straight longitudinal and transverse rows, the upper and lower edges of the fabric being connected to the corresponding cross-bars of the bed-frame by 20 one or more rows of helical springs to furnish the desired resiliency and elasticity in the bed bottom.

It is desirable, for reasons of economy, to 25 maintain insofar as possible, uniformity of form and structure in the elements or units of the fabric, since obviously a variety in this regard entails more complex machinery for manufacture of the units and correspondingly adds to the manufacturing cost.

A leading object of my invention, therefore, has been to produce a fabric composed exclusively of a single form and structure of unit capable of being readily assembled and 35 combining both strength and lightness. A known style of bed bottom fabric at the present time is composed of a series of parallel longitudinal strands each composed of duplicate units connected end to end, with transverse links flexibly connecting adjacent strands. In my present invention I have modified this type of fabric by eliminating the transverse connecting elements or cross-links as separate and distinct elements, substituting therefor integral lateral extensions 40 at one end of the units which are directly interhooked with each other in adjacent longitudinal strands to thereby produce without the aid of separate and distinct cross-links, the transverse space-filling and strand-connecting parts essential in a fabric of this character.

The invention will be readily understood when considered in connection with the ac-

companying drawing illustrating an approved mechanical form thereof, in which,

Figure 1 is a plan view of a portion of a bed bottom frame and fabric, the latter being broken out intermediate its ends. Fig. 2 is an edge view of Fig. 1, with the end bars of the frame appearing in cross-section. Fig. 3 illustrates a modified form of edge strand.

Referring to the drawings, 10 designates one of the longitudinal side bars of the bed frame, and 11 and 12 the upper and lower end or cross-bars, respectively, which bars are conveniently and cheaply formed of angle-bars and secured by bolts 13 and nuts 14. The cross-bars 11 and 12 have their up-standing flanges apertured as shown at 15 for the reception of the end hooks of the usual series of helical springs 16 and 17 through which the upper and lower ends of the fabric are commonly united with the upper and lower cross-bars of the frame, to furnish the desired resiliency and elasticity.

Referring now to the fabric itself, in which the novel features of the present invention more particularly reside, this fabric is made up of a series of parallel longitudinal strands each formed of duplicate or substantially duplicate bent wire units connected end to end, which units are provided at one end with integral lateral extensions adapted to be interhooked midway between adjacent strands to connect the latter, as well as form space-filling elements for the support of the superposed mattress. Each of the units is formed from a single length of wire of suitable gage, according to the load to be sustained, which wire is bent double at its longitudinal center, thereby forming a pair of closely adjacent parallel longitudinal limbs 18 having at one end thereof a downwardly turned loop or bight 19 of sufficient width to embrace the longitudinal limbs 18 passed therethrough, the wire forming said limbs at the other end of the latter being bent laterally at a right angle to form integral extensions 20, these latter terminating in hooks 21. The hooks 21 of each unit are bent to lie in planes at right angles to each other for suitable engagement with the hooks of adjacent units and so as not to project above the plane of the upper surface of the fabric; the hooks being preferably, and as herein shown, disposed in oppositely in-

clined planes lying at substantially an angle of 45 degrees from the plane of the fabric itself, although one hook may be disposed in a horizontal plane and the other in a vertical plane, if desired. A transverse row of units at that end of the fabric in which the open ends of the units lie adjacent to the helicals may omit the lateral projections 20, the longitudinal limbs terminating in simple hooks 22 that directly engage the adjacent end hooks of the helicals. To form a suitable edge for this fabric a simple straight wire 23 is shown in Fig. 1, the same being connected to and stretched between the end helicals of the series, and the lateral projections 20 of the adjacent longitudinal row of units being directly hooked thereover. In lieu of these wires 23, however, the edge strands may be formed by a connected series 20 of units 23^a of a slightly modified form, as shown in Fig. 3, which omits the integral extension 20 on the outer side, a simple hook 22, such as is shown on the upper transverse row of units, taking the place thereof.

It will be observed from the foregoing that the longitudinal and lateral limbs of the units of this fabric are simple straight wires and hence non-extensible. In some older fabrics of this class it has been common to render the fabric elastic or yielding between its ends, either through the introduction of one or more transverse rows of springs, or

by making the units themselves longitudinally elastic and yielding; but later practice has demonstrated that the proper place for the springs is at the ends of the fabric, thus preventing bowing and sagging of the fabric, which is an undesirable characteristic. By thus forming both the longitudinal and transverse limbs of the units of straight non-extensible wires, both longitudinal and transverse stretch of the fabric itself is eliminated. The fabric of this invention can be easily assembled either by hand or machinery, thus saving the expense involved in shipping the fabric in assembled form.

I claim:

A bent-wire unit for a bed-bottom fabric, comprising a pair of straight parallel longitudinal limbs provided at one end with a downwardly turned transverse loop or bight adapted to receive the longitudinal limbs of a similar unit, and at the other end with oppositely extending straight lateral extensions terminating in hooks adapted to engage corresponding parts of laterally adjacent units, said last-named hooks on opposite sides of the unit lying in planes substantially at right angles to each other.

CASSIUS H. HALSTEAD.
